I. M. PEASE
TRUSS CONSTRUCTION
Filed Feb. 5, 1925

Fig. 1.

INVENTOR:

Isaac M. Pease.

BY Richard Eivald,

ATTORNEY.

UNITED STATES PATENT OFFICE.

ISAAC M. PEASE, OF CINCINNATI, OHIO, ASSIGNOR TO THE OHIO TRUSS COMPANY, A CORPORATION OF OHIO.

TRUSS CONSTRUCTION.

Application filed February 5, 1925. Serial No. 7,115.

My invention relates to truss constructions.

The principal object of this invention is to provide an adjustable truss which is so arranged that the same may be fitted and adjusted to the back of the wearer so as to relieve the spinal column from rubbing and other irritation. In truss constructions as at present employed, the spring or strap 10 passing around the back of the wearer rests upon the spinal column, and the irritation set up by the strap and spring is such as to chafe and injure the skin and flesh of the wearer, sometimes to such degree that he is 15 compelled, at least periodically, to discard the truss entirely until the sores and irritation may be relieved. It is to obviate this difficulty that the present invention is directed.

20 In the drawings:

Figure 1 is a perspective view of part of a truss spring constructed in accordance with this invention, taken from the front.

Figure 2 is a perspective from the rear.

25 The numeral 1 indicates a continuous spring which is adapted to receive by means of extensions 2, or otherwise, front remedial or supporting pads 3 which may be of any desired construction and shape suitable to 30 the purpose for which the truss is intended. The continuous spring 1 is provided with a leather sheathing or cover 4 in accordance with the usual practice. The central back portion of the spring 1 is bent outwardly, as 35 shown at 5, and said portion may or may not be provided with a leather or other sheathing 6. The spring 1 is adapted to receive on opposite sides of the outwardly bent portion 5 adjustable pads 7 which are arranged to

bear upon the back of the wearer on opposite sides of the spinal column to support the truss with the front pads 3 in the proper position. The pads 7 are longitudinally adjustable on the spring, along straight sections 1^a and 2^a, by means of their sliding 45 supports 8, the suitable adjustment being retained by means of lock screws 9.

It will be seen from the foregoing description that a truss constructed in accordance with this invention is adapted to be 50 fitted to the wearer in such a manner that the spinal column is entirely relieved of rubbing and irritation. This is accomplished in part by the rear bend in the spring at 5, as clearly shown in the drawings, and further by the adjustment of the pads 7 in such a manner that the spring is entirely removed from contact with the wearer between said pads. The point of irritation over the spinal column, which is a source of extreme 60 suffering and annoyance, is therefore entirely relieved and the comfort of the wearer greatly promoted.

Having thus fully described my invention, what I claim as new and desire to secure by Letters Patent is:

A truss construction comprising a continuous spring adapted to pass around the back of the wearer and to support a remedial pad in front, said spring being provided with a 70 rearwardly bent section arranged to clear the spinal column of the wearer, pads on opposite sides of said rearwardly bent section, said pads being slidably adjustable on said spring, and means for securing said pads 75 when adjusted.

ISAAC M. PEASE.
